Apt. 902D, Chicago, Ill. 60610

Filed Oct. 30, 1974, Ser. No. 519,126

Term of patent 14 years

Int. Cl. D23—02

U.S. Cl. D23—71

FIG. 1 is an end elevational view of a handle for a toilet seat or the like showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is an elevational view taken from the end opposite that shown in FIG. 1.

The fragmentary broken line representation of a toilet, toilet seat and toilet seat cover in FIG. 1 is for purposes of illustration only.

I claim:

The ornamental design for a handle for a toilet seat or the like, as shown and described.
